UNITED STATES PATENT OFFICE

GEORGE T. JOHNSON AND GEORGE E. LARGE, OF COLUMBUS, OHIO, ASSIGNORS TO THE
BUCKEYE STEEL CASTINGS COMPANY, OF COLUMBUS, OHIO

CAR END

Application filed July 16, 1929. Serial No. 378,789.

This invention relates to improvements in car ends, and more especially to a novel one-piece metallic end for freight cars and the like.

5 The main objects of the invention are to provide improved means for reinforcing the car end against bulging and to improve the corner constructions of the casting.

It is well known that car ends of the built-up type have many objections.

For instance, the built-up construction soon becomes considerably bulged and otherwise distorted, due principally to endwise shifting of loose lading, and to careless handling of unloading crane buckets, so that the construction soon demands repair or replacement. As the sheet portion of a built-up car end is thin, (one-quarter to five-sixteenths inches), when it is bulged, the rivet holes tear 20 or the rivets loosen, and such loosening of the connection destroys its strength. Furthermore, the distortion of the car end is communicated to the brake shaft which is attached thereto, and this interferes with the 25 safe and efficient operation of such staff. For reinforcement purposes, H-beams are often placed horizontally across and outside the end of the car at intermediate levels, in order to stiffen the car ends, but they too bend outward, and also collect dirt and water.

Heretofore, it has been proposed to eliminate such difficulties by furnishing a one-piece cast metal car end, and another object of the present invention is to provide a one-piece metallic car end possessing a number of advantages over the known cast metal car end.

With the foregoing objects outlined and with other objects in view which will appear 40 as the description proceeds, the invention consists in the novel features hereinafter described in detail, illustrated in the accompanying drawings, and more particularly 45 pointed out in the appended claims.

Referring to the drawings,

Fig. 1 is a front elevation of our improved car end.

Fig. 2 is a top plan view of the same.

50 Fig. 3 is an end elevation.

Fig. 4 is a vertical sectional view on the line 4—4 of Fig. 1.

These drawings show what we now consider the preferred embodiment of the invention, and in this one-piece metal car end, the main web is shown at 13, and it is provided at its upper corners with the top corner connections 1, which are horizontally disposed and are adapted to be attached to the top bulb irons 1a, which extend along the 55 sides of the car.

The web is provided at its side edges with inwardly extending relatively wide flanges 2, which are apertured to receive the rivets or the like employed in connecting the side edges of the end to the sides of the car. The web is also shaped adjacent to one of its side edges to form integral inside sters 3, 4 and 5, and at the point where the step 5 is located, an air 60 brake pressure retaining valve bracket 6 is located. The end sill portion of the car end is shown at 7, and the entire casting has all the necessary reinforcement and cored holes 65 ready to apply to the car.

The American Railway Association safety 70 appliance rules do not allow any part of the end of a standard freight car to extend beyond the plane 8—8 of the face of the striker, with the exception of certain brake parts. Ordinarily, the end sheet of the built-up construction heretofore used, will be arranged 75 at the plane 9—9, with the end sill projecting beyond it to about the plane 10—10, as shown in Fig. 4.

It will therefore be seen that as the plane 85 9—9 is about the limit of lading space for the built-up construction, the reinforcing members (outside) will project to, or beyond the plane 10—10, and outside ladder rungs, etc., sometimes must be attached to these 90 members, thus using up the remaining space out to the plane 8—8. By placing the main horizontally disposed reinforcing parts 11 and 12 inside the web portion 13, the cubic content of the car is appreciably increased, 95 without projecting the end any farther outward than the built-up construction, and without even having longer side sheets. In other words, by utilizing relatively wide side flanges 2, and arranging the main reinforce- 100

ments 11 and 12 inwardly of the main web 13, we are able to obtain the increased capacity of the space between the planes 9—9 and 10—10.

5 It will be noted that the reinforcement of the car end against bulging, consists in part, of these two horizontal channel-shaped portions 11 and 12, which project inward from the web 13, and are themselves reinforced 10 by vertical ribs 14, 15 and 16. The rib 14 preferably extends the full height of the car sides, being at certain points, inside the web 13, and at other points, outside of the latter. At the points where it is outside of the web, 15 it spans the channel shaped reinforcements 11 and 12. These ribs stiffen the structure against vertical blows which may be suffered in loading. The reinforcement 11 has a depression in its upper portion which forms the 20 step 4.

The reinforcement 11 tapers toward its ends, as indicated at 11a in Fig. 2, as great strength will not be needed at the ends as at the medial portion of this part, and this reinforcement 25 also prevents the minimum section 17 of the casting from being too small. At the points 18, where the reinforcement ends, the web 13 curves around to meet the side sheets on very large radius curves, thus reducing 30 the chance for cracks, not only along these lines, but over the full height of the car sides. These rounded corners to the car not only make a pleasing and substantial appearance, but actually strengthen it much 35 more than square corners would.

We prefer to provide the inside steps 3, 4 and 5 with upwardly extending wings 3a, 4a and 5a to prevent the brakeman's foot from sliding off laterally, and the step 5 has combined with it, the retaining valve bracket 40 6, which allows connections to be made from the exterior of the car, even while the latter is loaded. Furthermore, the inside steps are located beside the outside ladder, (not 45 shown), for greatest convenience.

It will be observed that the two reinforcing channels 11 and 12, as well as the inside steps are so designed that they present inclined or sloping surfaces within the car, and 50 no free edges, so that unloading crane buckets, etc., cannot catch upon them in their upward movement.

The edge 12a is heavily beaded to a smooth 55 "bulb", both for strength and safety, and the top inside corner details at 19, are quite stiff and easily made by this method, and nothing can catch upon them.

The lower horizontal portion or shelf 20 60 also stiffens the car end against bulging, and seals the car floor against corrosion, and it will be noted that the end sill portion 7 (extending below the level of the car floor), may, or may not be used, depending on the 65 particular circumstances of each case. Note

also that provision is made for receiving the lower side angles at 21.

Our car end has been designed to fit inside the side sheets of the car, while heretofore, one-piece car ends have been designed to 70 fit outside of the side sheets. Our improvement has the advantage that no deep notch need be made in the upper corners of the casting to receive the top side bulb angles. This may be clearly understood by reference 75 to Fig. 2, in which the side sheets are indicated at 21a.

The new design also has foundry advantages over the ones previously known. Were 80 it not for the rivet holes, and the details at 6 and 21, it would require no coring at all. This is a very substantial reduction over the earlier designs. Furthermore, the arrangement of the reinforcing ribs within the car end 85 also keeps the depth 22 within proper bounds.

While we have not shown such details as 90 push pole pockets, jacking pads, and emergency chain pull holes, it is obvious that such features may be incorporated in our car end 95 if desired.

In general, the integral construction allows 100 metal to be removed from places where it is not useful, and to be placed at points where needed. It presents smooth rounded surfaces and fewer joints, reduces corrosion and accidents to a minimum, and eliminates points of stress concentration. It also saves the work incident to collecting and fitting many separate parts. The number of rivets particularly, is reduced, as is also the completed weight.

From the foregoing it is believed that the 105 construction, and advantages of the invention may be readily understood, and it is manifest that changes may be made in the details disclosed, without departing from the spirit of the invention, as expressed in the claims.

What we claim and desire to secure by 110 Letters Patent is:

1. A metallic car end having integral inwardly extending substantially horizontal channel-shaped reinforcements, a horizontal top flange and projecting side flanges formed by continuations of said top flange. 115

2. A metallic car end including a web and reinforcements integral with the web, and arranged inwardly of the outer surface of the latter, the upper portion of one of said 120 reinforcements being continued to form projecting side flanges.

3. A metallic car end including a web provided with inwardly extending substantially channel-shaped reinforcements which are 125 integral with the web, and integral vertical ribs within said reinforcements.

4. A metallic car end including a web provided with an integral inwardly extending substantially channel-shaped reinforcement, 130

- extending from one edge portion of the web to the opposite edge portion of the same and having vertical ribs therein.
5. A metallic car end provided with a pair of integral channel-shaped reinforcements which extend inwardly from the web and are spaced from one another, the upper portion of one of said reinforcements forming a top flange for the car end.
10. 6. A one-piece metallic car end including a web, and substantially channel-shaped reinforcements integral with the web and projecting from the inner surface of the latter, said reinforcements having vertical ribs within the same.
15. 7. A one-piece metallic car end including a web, and substantially channel-shaped reinforcements integral with the web and projecting from the inner surface of the latter, the upper portion of one of said reinforcements forming a top edge and each of said reinforcements having a sloping under surface as and for the purpose set forth.
20. 8. A one-piece metallic car end including a web, and substantially channel-shaped reinforcements integral with the web and projecting from the inner surface of the latter, the upper surface of one of said reinforcements having a depression therein forming a step.
25. 9. A one-piece metallic car end comprising a web provided with integral substantially horizontally arranged channel-shaped reinforcements which extend inwardly from the rear surface of the web, the upper portion of one of said reinforcements forming a top edge for said car end.
30. 10. A one-piece metallic car end comprising a web provided with integral substantially horizontally arranged channel-shaped reinforcements which extend inwardly from the rear surface of the web, and substantially vertically disposed ribs arranged within and reinforcing said channel-shaped portions.
35. 45. 11. A one-piece metallic car end comprising a web provided with integral substantially horizontally arranged channel-shaped reinforcements which extend inwardly from the rear surface of the web, and substantially vertically disposed ribs reinforcing said channel-shaped portions, one of said ribs being arranged at the medial portion of the car end and extending throughout substantially the entire height of the web.
40. 50. 55. 12. A one-piece metallic car end comprising a web provided with integral inwardly extending reinforcements, a top edge formed by the upper portion of one of said reinforcements and flanges integral with the side edges of the web and extending inwardly from the latter for attachment to the sides of the car.
55. 60. 65. 13. A one-piece metallic car end having at its top portion an integral substantially channel-shaped inwardly extending reinforcement, a shelf projecting inwardly from the lower portion of the web, and a rib integral with the web and having its ends merging into the channel-shaped reinforcement and shelf.
14. A one-piece metallic car end including a web having its side edge portions curved and terminating in substantially parallel flanges.
15. A one-piece metallic car end including a main web provided about midway between its upper and lower edges with an integral substantially channel-shaped and substantially horizontally disposed reinforcement, which projects inwardly from the inner surface of the web, the end portions of the reinforcement tapering toward the web, and reinforcing ribs arranged within and integral with said channel-shaped part.
16. In a metallic car end, a web projected inwardly to provide an inside step, the web adjacent to said step forming a retaining valve bracket.
17. A metallic car end including a web having an integral pocket projecting inwardly from the inner surface of the web, a portion of the web extending across the mouth of the pocket and forming a retaining valve bracket.
18. In a one-piece metallic car end, a web provided with an inwardly extending integral inside step provided with upwardly extending side wings.
19. A one-piece metallic car end including a main web having its side edge portions curved to form relatively wide side flanges, and integral reinforcements for the web projecting inwardly between the side flanges, and of less width than the latter.
